(57) **CLAIM**

The ornamental design for an exercise kiosk, as shown and described.

DESCRIPTION

FIG. 1 is a perspective view of my exercise kiosk; FIG. 2 is a front view thereof; FIG. 3 is a rear view thereof; FIG. 4 is a left side view thereof; FIG. 5 is a right side view thereof; FIG. 6 is a top view thereof; and FIG. 7 is a bottom view thereof; FIG. 8 is a perspective view thereof with the arms deployed for use; FIG. 9 is a front view thereof with the arms deployed for use; FIG. 10 is a back view thereof with the arms deployed for use; FIG. 11 is a left view thereof with the arms deployed for use; FIG. 12 is a right view thereof with the arms deployed for use;

FIG. 13 is a top view thereof with the arms deployed for use; FIG. 14 is a bottom view thereof with the arms deployed for use; and,

FIG. 15 is a perspective view thereof with the arms deployed for use and a phantom user shown for context.

The broken line portions of the disclosure are included for the purpose of illustrating environment and form no part of the claimed design.

1 Claim, 13 Drawing Sheets
